UNITED STATES PATENT OFFICE.

ARTHUR W. EASTON, OF BUFFALO, NEW YORK.

CLIP FOR USE WITH PENCILS OR FOUNTAIN PENS.

Application filed May 19, 1926. Serial No. 110,123.

This invention relates to improvements in clips for use with pencils or fountain pens for the purpose of holding such articles in a pocket of a vest or coat. More particularly 5 the invention relates to a combination clip and blade and proposes a construction wherein the blade is so combined with the clip that it is normally invisible or at least unnoticed and may, without disconnection 10 from the clip, be moved to a position for use for any purpose desired, for example, for use as an eraser or letter opener.

The invention consists in the novel features of construction and arrangement which 15 will be set forth in detail as the description proceeds.

In the accompanying drawing in which the embodiment of the invention is illustrated:

20 Figure 1 is a front elevation of the clip as applied to a fountain pen;

Figure 2 is a longitudinal sectional view of the clip as applied to a fountain pen.

Figures 3, 4 and 5 are sectional views on 25 the respective lines 3—3, 4—4 and 5—5 of Figure 1;

Figure 6 is a perspective view of the blade which is combined with the clip;

30 Figure 7 is a detail sectional view showing the blade in course of its adjustment from one position to another.

The clip may be mounted on a pencil or fountain pen in various ways. In the construction shown in the drawing the clip is 35 carried by the split spring band 1 which encircles the cap of the fountain pen near its outer end. The clip proper consists of an elongated spring member 2 which at one end is formed with an angular shoulder 3 by which the clip is joined to its means of 40 attachment, in this instance the band 1, and at the opposite end is formed with a ball-shaped part 4 which under the pressure of the spring 2 engages frictionally with the 45 wall of the pocket in the well-known manner.

According to the invention the spring 2 is formed between the ball 4 and the shoulder 3 with a slot 5 and the shoulder is formed 50 with an opening 6. The said slot and opening are provided for cooperation with a blade 7 which normally lies under the spring 2 with its outer end within the opening 3 as shown in Figure 2. The blade 7 is formed 55 at its inner end with an angular shoulder 8 which extends through and works in the

slot 5 and normally engages the inner end of the slot. Beyond the shoulder 8 the blade 5 is formed with a dished projection 9 which conformably engages over the ball 4 and holds the blade in its retracted position. The shoulder 8 and the projection 9 have a certain measure of resiliency whereby the projection 9 will engage frictionally with the ball 4 and will not become accidentally 60 displaced, thereby insuring that the blade 7 will normally lie under the spring 2 in a position where its presence will not be noticeable and where it will also aid the function of the ball 4 in securing the fountain 65 pen or similar object in the pocket.

When it is desired to use the blade the projection 9 may be sprung from engagement with the ball 4 as shown in Figure 7. This is readily accomplished by applying 70 the thumb nail under the outer edge of the projection 9 and springing the same back from engagement with the ball 4. At such time the blade may be projected beyond the cap of the fountain pen as shown by broken 75 lines in Figure 2 and in this position it may be used for any purpose desired. In using the blade the same may be held in its outermost position by finger pressure applied 80 against the end of the projection 9; or it may, as shown, be held in its projected position by means of a spring latch 10 which is secured to the outer face of the spring 2 and which may be engaged behind the shoulder 8. The latch 10 may be of any suitable 85 construction, for example, the construction commonly employed in jewelry clasps. When the blade is restored to normal position the projection 9 springs over the rounded wall of the ball 4 and by its own 90 resiliency and the resiliency of the part 8 frictionally engages said wall in the manner shown and described.

Having fully described my invention, I 95 claim:

1. A clip for the purpose described comprising an elongated flat spring having at one end means for its attachment to a fountain pen or the like, said means including a shoulder extending angularly from said spring, and having at its other end an engaging ball, said spring having a longitudinal slot and said shoulder having an opening, and a blade arranged under said spring with its outer end lying in said opening, said blade having at its inner end an angular resilient shoulder which projects 100

- through said slot and having also a part which projects from said shoulder and conformably engages said ball, said blade being thereby normally held under said spring and upon the disengagement of said part from said ball being movable lengthwise of said spring to project beyond the same.
2. A clip for the purpose described comprising an elongated flat spring having at one end means for its attachment to a fountain pen or the like and at its other end an engaging ball and a blade slidable lengthwise of said spring and having at its inner end a resiliently acting part which conformably engages said ball to hold said blade in a normal position, said blade upon the disengagement of said part from said ball being movable lengthwise of said spring to project beyond the same.
3. A clip for the purpose described comprising an elongated flat spring having at one end means for its attachment to a fountain pen or the like and at its other end an engaging ball and a blade slidable lengthwise of said spring and having at its inner end a resiliently acting part which conformably engages said ball to hold said blade in a normal position wherein it lies under said spring, said blade upon the disengagement of said part from said ball being movable lengthwise of said spring to project beyond the same.

In testimony whereof I affix my signature.
ARTHUR W. EASTON.
